LIQUID FILTER

Frederick R. Gruner, Westfield, N.J., assignor to Purolator Products, Inc., Rahway, N.J., a corporation of Delaware

Filed June 23, 1960, Ser. No. 61,085

Term of patent 14 years

(Cl. D46—1)

FIG. 1

FIG. 3

Fig. 1 is a side elevational view of a liquid filter embodying my new design;

Fig. 2 is a top plan view thereof; and

Fig. 3 is a bottom plan view thereof.

I claim:

The ornamental design for a liquid filter, substantially as shown.
